(57) **CLAIM**

The ornamental design for an intraocular lens, as shown and described.

DESCRIPTION

FIG. 1 is a front view of an intraocular lens showing my new design;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is a perspective view thereof; and,

FIG. 8 is an enlarged sectional view thereof taken on line 8-8 of FIG. 1.

The Broken line showings of FIGS. 1-8 are environmental only and not part of the claimed design.

The dashed-dotted line showings of FIGS. 2-7 illustrate a boundary between the claimed design and environmental features and form no part of the claimed design.
